Claims priority, application Germany Feb. 5, 1959
9 Claims. (Cl. 18—16)

My present invention relates to a multi-platen press and, more particularly, to platen-spacing means for such presses.

Multi-platen presses, and primarily those employed for the heated compression and curing of cellulose-fiber sheets (e.g. fiberboard), have been provided heretofore with lazy-tongs or similar mechanisms adapted to maintain the spacing between the several platens during the closing of the press. These lever linkages do not, however, compensate effectively for the omission of sheets as a result of a faulty press-charging operation or for the varying thicknesses of the sheets. Thus, the major compacting force of a hydraulic press bed is often applied only to a few of the charged sheets, or unequally to the entire charge.

It is, therefore, the general object of my invention to provide a multi-platen press adapted to obviate the above-mentioned disadvantages.

A more specific object of the invention is to provide improved platen-spacing means for multi-platen presses.

According to a feature of my invention, the sheet-supporting platens of a multi-platen press are elevated concurrently with the elevation of the bed plate, but at different rates corresponding to the distance each platen must be vertically displaced to reach the point at which compression of the charge between the bed plate and the head plate of the press commences. Generally speaking, the lowest platen (nearest the bed plate) will require the greatest displacement while the uppermost platen (nearest the head plate) will require the least. Upon reaching the point at which pressure is applied by the bed plate, or at least the point in the closing of the press at which such pressure would normally commence in the presence of a full charge, the platen-spacing apparatus is rendered inoperative, in accordance with the invention, so that no mechanical strains will develop from any unequal spacings as caused, for example, by the absence of one or more rough sheets between the platens or from differences in the thicknesses of the inserted sheets. Advantageously, the platen-spacing apparatus may subsequently be caused to function again for the gradual lowering of the platens after compaction or at some other point in the press cycle to assist in readying the press for the next charge.

According to another feature of the invention, the platens are raised and lowered by individual mechanical links preferably in the form of cables secured to a suitable transmission member, such as a step pulley. The cables attached to the lowest platens may then engage the largest-diameter steps of the pulleys while the successively higher platens are connected with respective smaller-diameter steps. Thus, upon rotation of the pulleys either independently of or in response to the elevation of the bed plate, the step pulleys take up the cables in proportion to the required vertical displacement of each platen, thereby closing the press gradually and smoothly and without requiring the bed plate or the lower platens to support upper, unloaded platens. Advantageously, the rotation of the pulleys may be coupled to the movement of a hydraulically elevatable structure, e.g. the bed plate itself, via tractive members and suitable direction-changing means whereby the closure stroke of the bed plate prior to compression is utilized to operate the spacing apparatus. The latter may then be ren-

2

dered inoperative, for the purpose mentioned above, by slackening the tractive members.

According to a more specific feature of the invention, the spacing apparatus is uncoupled from the drive means therefor by halting the rise of the elevatable structure accompanying the closing movement of the bed plate while permitting the latter to continue its stroke, thereby compressing the sheets while concurrently slackening the cables. The spacing apparatus may also be engaged or disengaged by means of electrical and hydraulic control circuits actuated directly by the motion of the bed plate.

The above and other objects, features and advantages of my present invention will become more readily apparent from the following description, reference being made to the accompanying drawing in which:

FIG. 1 is a somewhat schematic front-elevational view, with parts broken away and in section, of a multi-platen press according to the invention;

FIG. 2 is a view, similar to FIG. 1, of a second embodiment of the invention;

FIG. 3 is a side-elevational view, with parts broken away, of the embodiment of FIG. 2; and

FIG. 4 is a schematic circuit diagram of this embodiment.

In FIG. 1 I show a multi-platen press in the open condition thereof, comprising a generally rectangular frame 1. A bed plate 3, vertically displaceable by a hydraulic piston 2b received in cylinder 2a, is provided between the front and rear members of frame 1 to compress roughly formed cellulose-fiber sheets 21, carried on a plurality of vertically spaced platens 4, against a head plate 20. The platens 4 are each supported by four cables 6 depending from step pulleys 5 journaled at the four upper corners of the press frame. The pulleys 5 are provided with steps of progressively increasing diameter, respectively proportional to the requisite displacement of each platen during the closing of the press. The uppermost platen is therefore connected to the smallest diameter step while the cables 6 of the lowest platen are secured to the largest-diameter step. Advantageously, the cables are joined to the platens 4 at lugs 22, dimensioned and staggered to maintain the cables in plumb despite the different radii and axial spacing of the steps. Each pulley 5 is driven by a cable 7 secured to the driving step thereof and partly wound therearound. The cables 7 are passed about direction-changing and tensioning pulleys 8 and connected to bed plate 3 at lugs 23. Each pulley 8, at one of the four lower corners of the press frame 1, is supported on a vertically displaceable piston 9 received in a cylinder 14. Each pulley 5 is also provided with a ring of ratchet teeth 24 engageable by a pawl 11. The latter may be removed from engagement with the ratchet teeth by a release mechanism 12, such as a solenoid, actuatable via an electric circuit arrangement comprising a source of current 25 and a pressure-sensitive switch schematically indicated at 26. The master compression cylinder 2a is supplied with fluid from a reservoir 27 via a pump 28, a pressure valve 29 and a distributing valve 33, while the cylinders 14 are supplied with fluid from the pump via valve 29.

In operation, upon the charging of the press with the sheets 21, the handle of distributing valve 33 is actuated to permit a flow of fluid under pressure from the pump 28 through valve 29 and by way of conduits 32 and 34, to the cylinder 2a, thereby raising piston 2b and bed plate 3. Simultaneously, fluid flows from the pressure main 35 through valve 29 and a bore provided in the armature 29' thereof to conduit 30. From this conduit, fluid enters the cylinders 14 above the head of pistons 9, thereby locking these pistons in the position shown in FIG. 1 to tension the cables 7. As bed plate 3 rises

to close the press, the vertical movement of the plate is transformed into a rotary movement of the step pulleys 5 via cables 6. The cables 6 are thus wound about their respective steps to elevate the platens 4 at a rate proportional to their distance from the head plate 20. When one or more platens 4 begin to exert pressure upon the sheet or sheets 21 of greatest thickness, the resulting increase in the hydraulic pressure within the master cylinder 2a is transmitted to pressure valve 29 and causes a downward displacement of the diaphragm 29a thereof along with the plunger 29' secured thereto. The bore of this armature then becomes aligned with that of return tube 36 whereby fluid can return from cylinders 14 through conduit 31 into the reservoir 27. Piston 9, no longer held against vertical displacement by fluid pressure, rises under the tension of cable 7 to slacken the latter so that further elevation of the bed plate 3 will not transmit motion to the pulleys 5 which are locked against reverse movement by the pawls 11 engaging appropriate teeth of their ratchet rings 24. When the hydraulic pressure attains a predetermined maximum, switch 26, linked with valve 29 by a tube 26', is tripped to activate solenoids 12, thereby disengaging the pawls 11 from toothed rings 24 and freeing the pulleys 5 for reverse rotation. After a curing period at maximum pressure, valve 33 may be reversed to exert downward pressure upon piston 2b via a tube 34' and to drain the fluid from the master cylinder 2a via tube 37 while bypassing a limited quantity of fluid from the pressure valve 29 to the reservoir through tubes 32 and 37. The pressure in the valve thus drops, the diaphragm 29a thereupon raising the plunger 29' to its original position to re-open the fluid path to the cylinders 14; this again tensions the cables 7 upon the descent of pulleys 8 to permit the downward movement of the bed plate 3 to lower the platens gradually and at different rates. As the bed plate 3 comes to rest in its bottom position, the reduced pressure in the valve 29 restores switch 26 and, therefore, solenoids 12 to normal, thus permitting the pawls 11 to re-engage the teeth of ratchets 24 as the bed plate 3 rises for another press cycle.

In FIGS. 2 and 3 I illustrate another embodiment of the invention wherein the bed plate 3 is adapted to compress a plurality of sheets 21 carried by the platens 4 against a head plate 20 as described hereinabove. The platens are again supported from four step pulleys 5 by cables 6 secured to the platens 4 or bars 22. In the present embodiment, however, the tractive elements 7, adapted to drive the pulleys 5, pass under idler pulleys 38 not displaceable in a vertical direction. The elements 7 are joined to a pair of yokes 17 (one of which is shown) extending at least partially beneath and transverse to the bed plate 3, these yokes being elevatable by a pair of hydraulic cylinders 16b whose pistons 16a bear thereon from below. Bed plate 3 is also carried on pistons 2b of master cylinders 2a. The electrical circuit arrangement for the present embodiment is further illustrated in FIG. 4. Each platen 4 and the head plate 20 is provided with one of a plurality of series-connected switches 41a to 41h which are closed by the engagement of their armatures with the next-lower platen 4 or with the bed plate 3. A second set of switches 37a to 37h, closable directly by platens 4 or bed plate 3 and connected in parallel, are similarly provided on each platen 4 and the head plate 20. A normally closed limit switch 45 is mounted on the base of the press so as to be open-circuited upon the down-stroke of yoke 17 by a stud 43 carried thereon. The parallel combination of switches 37a to 37h is connected in series with the drive motor 44 of a hydraulic distributing valve 40 and with a source 43 of electric current, while the series-connected switches 41a to 41h are connected in a circuit including an electromagnetic holding relay 55 and the battery 43. The relay contacts 55a, 55b lie in series with parallel-connected solenoids 12, previously described, and the battery 43, while switch 45 is inserted in the holding circuit of relay 55.

In operation, hydraulic fluid from reservoir 27 is forced by pump 28 through a transmission tube 50 to the master cylinders 2a while a part of the fluid enters the cylinders 16b via tube 52, thereby raising the yokes 17 and the bed 3. It will be apparent that the flow of fluid may be so regulated as to permit the yokes to raise the bed plate 3 or to cause the substantially simultaneous elevation of both yokes and the bed plate. The press thus closes until one or more of the parallel switches 37a to 37h operate. Thereby an electrical circuit is closed to drive motor 44 which adjusts the distributing valve 40 to shut off the flow of fluid to cylinders 16b while continuing the flow under increased pressure to master cylinders 2a. The upward motion of the yokes 17 thus ceases whereas the bed plate 3 commences its compression stroke, thereby slackening the cables 6 and 7 to disengage the spacer apparatus. At the conclusion of the compression stage, i.e. when all the sheets have been compressed to their predetermined thicknesses, the series-connected switches 41a to 41h close to complete a circuit to the winding of relay 55, thereby closing the contacts 55a, 55b and operating the solenoids 12 to withdraw the pawls 11 from engagement with their ratchet rings as described with reference to the preceding embodiment. After a predetermined curing time has elapsed, the motor 44 in its continuing operation blocks the fluid flow to cylinders 2a and opens a return path from the latter to the reservoir 27 via return tube 56. The bed plate thus commences to lower, entraining in the latter part of its descent the yokes 17 to re-activate the spacer mechanism. The distributing valve 40 may be designed to introduce fluid at this time to the tops of cylinders 16b and 2a via tubes 53 and 51, respectively, to increase the rate at which the press opens. As the yokes 17 and the bed plate 3 attain the fully opened position of the press, plunger 43 trips the normally closed switch 45 to deactivate the relay 55, thereby releasing pawls 11 and restoring the spacer assembly to operative condition preparatory to a new charge.

Abutments 57 (only one shown) on the frame 1 of the press serve as safety stops for the yokes 17 to insure a slackening of the cables even upon failure of the switching circuit 37a to 37h. In cases where major differences in sheet thickness and partial loading of the press are no problem, such abutments (positioned, if desired, at a somewhat lower location on the frame) may also be used in lieu of such switching circuit as means for deactivating the spacing apparatus at a predetermined point in the ascent of the bed plate 3. Under such circumstances it would also be possible to dispense with all but one of the switches 37a to 37h and to mount the remaining switch on the frame 1 for actuation by one of the yokes 17 (FIG. 2) or by the bed plate 3 (FIG. 1 or 2) as the latter reaches the point at which slackening of the cables is to occur. These and other modifications, which will be readily apparent to persons skilled in the art, are intended to be included within the spirit and scope of the invention except as further limited by the appended claims.

I claim:

1. A multi-platen press for the compaction of sheet materials, comprising a frame; a plurality of vertically spaced sheet-supporting platens held on said frame for vertical movement; a fixed stop on said frame above said platens; plunger means below said platens operable to act upon the lowermost platen in a manner pressing all of said platens and the intervening sheets against one another and said stop; operating means for raising said plunger means; transmission means coupled with said plunger means for raising said platens simultaneously with said plunger means at rates decreasing progressively from the lowermost to the uppermost platen whereby the separations between said platens concurrently decrease upon the rise of said plunger means, said transmission means comprising a stepped pulley, a set of cables passing

around respective stops of said pulley and anchored to respective platens, and coupling means including a further cable releasably interconnecting said plunger means and said pulley for rotating the latter upon a rise of the former; tensioning means bearing upon said further cable in a first direction tending to raise said platens through said transmission means for maintaining the connection between said pulley and said plunger means during at least part of the rise of said plunger means; and automatic means coupled with said tensioning means and controlled by said operating means for temporarily inactivating said coupling means at an intermediate point in the rise of said plunger means by slackening said further cable through a displacement of said tensioning means in a second direction opposite said first direction.

2. A press according to claim 1 wherein said operating means comprises a hydraulic system.

3. A press according to claim 2 wherein said automatic means is provided with an actuating element responsive to a rise in the hydraulic pressure of said system due to beginning compaction of at least one of said sheets.

4. A press according to claim 1, further comprising switch means controlled by at least one of said platens for operating said automatic means.

5. A press according to claim 1 wherein said tensioning means comprises a deflecting roller engaged by said further cable and said automatic means includes hydraulically displaceable support means for said deflecting roller.

6. A press according to claim 1 wherein said plunger means comprises a bed plate, said tensioning means comprising a follower member upwardly displaceable by said operating means along with said bed plate during a portion of the ascent of the latter, said further cable being anchored to said follower member.

5 7. A press according to claim 6 wherein said follower member comprises a yoke embracing said bed plate from below in a lower position of said bed plate, said automatic means and said operating means respectively including first and second hydraulic systems for respectively raising said yoke and said bed plate, said tensioning means further including stop means for inactivating said first hydraulic system.

10 15 8. A press according to claim 1, further comprising check means for locking said stepped pulley against reverse rotation and release means for de-activating said check means substantially upon attainment of its highest point by said plunger means.

20 9. A press according to claim 8 wherein said check means comprises a set of ratchet teeth on said pulley and pawl means engageable with said ratchet teeth, said release means including an electromagnetic device for retracting said pawl means from said ratchet teeth.
